CLAIM

The ornamental design for a pole mounted rotating speaker system, substantially as shown and described.

DESCRIPTION

FIG. 1 is a front, top and left side perspective view of a pole mounted rotating speaker system showing my new design, with the broken line structure included as environment only and forming no part of the claimed design;

FIG. 2 is a left side elevational view thereof; and FIG. 3 is a bottom plan view thereof.

FIG. 1

FIG. 2

FIG. 3
